UNITED STATES PATENT OFFICE.

JOHN WATTERS, OF NEW YORK, N. Y.

FRAME FOR CARRIAGE-CURTAIN LIGHTS.

SPECIFICATION forming part of Letters Patent No. 277,388, dated May 8, 1883.

Application filed February 2, 1883. (No model.)

To all whom it may concern:

Be it known that I, JOHN WATTERS, of the city, county, and State of New York, have invented a new and useful Improvement in 5 Frames for Carriage-Curtain Lights, of which the following is a specification.

My invention relates to an improved construction of metallic frames for carriage-curtain lights that combines neatness of finish with complete protection against the weather.

In the accompanying drawings, Figure 1 represents the two members of the frame detached. Fig. 2 is a transverse section, showing the completed joint.

15 A may represent a portion of a carriage-curtain, usually of leather lined with cloth, the same having an opening, *a*, slightly larger than the inner opening of the frame.

B is a portion of the light or pane of glass.

20 C and D respectively represent the inner and the outer frames, which are stamped out of sheet metal to any desired size and configuration. The frame C has a number of slots, *c*, to receive as many clips *d*, which, projecting

25 from the outer edges of the outside frame, D, are bent toward the center of the frame, as shown in Fig. 1. The light B being inserted in the outside frame, D, with its edge confined

by the clip-shoulders, the clip ends are forced through slits prepared in the curtain, and 30 through the slots *c* in frame C, and clinched around the outer edges of said frame, as shown in Fig. 2. The clips *d*, being projections of the outer edges of the outside frame, secure close 35 weather-proof contact of said edges with the curtain, and effectually exclude rain without exposing the cut edges of the curtain, thus securing a neat finish and avoiding decay or rotting of the stuff.

I claim as new and of my invention—

The fastening for carriage-curtain lights, consisting of the combination of slotted inner frame, C *c*, with the outer frame, D, whose clip projections *d* from its outer edges are bent inward to constitute abutments for the light, 45 and thence extend through the slots *c* of the inner frame, C, and are clinched around the outer edge of said frame, substantially as set forth.

In testimony of which invention I hereunto 50 set my hand.

JOHN WATTERS.
